APPARATUS FOR SPINNING ARTIFICIAL FILAMENTS

Richard W. Stanley, Drexel Hill, Pa., assignor to
American Viscose Corporation, Wilmington,
Del., a corporation of Delaware

Application April 22, 1944, Serial No. 532,328

21 Claims. (Cl. 18-8)

1

This invention relates to improved apparatus for continuously spinning artificial filaments or threads.

It is an object of the invention to provide an improved machine for continuously spinning, manipulating, and treating artificial threads in which the section of the machine carrying the coagulating liquids which are generally the most corrosive is so arranged with respect to the liquid after-treating section in which less corrosive liquids are used that there is little opportunity for spray from the coagulating bath and the thread handling devices associated with the coagulating bath to be carried over to the thread as it is discharged from the after-treating liquid section. Arranged intermediate the coagulating bath and the after-treatment section, there is provided in accordance with the objects of this invention, a stretching zone which forms a component part of what is hereinafter termed the forming section and in which the thread may be treated with any suitable plasticizing liquid, which in the case of viscose may be hot water or hot dilute acid. These two distinct sections of the machine are so arranged that the discharge end of the liquid after-treatment devices is at the part thereof farthest from the forming section and is beyond the reach of operators employed along the coagulating bath working face of the machine and conversely the forming section of the machine is out of reach of operators employed along the after-treatment working face of the machine.

A further object is to so arrange the sections of the machine that the entire spinning or treating unit of each single end thread-producing station will be readily and conveniently accessible to the operators assigned to the respective working faces of the machine. A further object is to provide a spinning machine having a compact liquid after-treatment section in which all of the after-treating liquids (excluding the stretching bath which is herein considered to constitute a forming liquid as distinguished from an after-treating liquid) are applied to a single continuous helix of the thread. The present invention also provides for drying and/or collecting the after-treated yarn in a section provided at a different floor level than that of the coagulating and after-treating sections.

A further object is to provide an arrangement and system whereby the driving mechanism for the thread handling devices in both the spinning and after-treatment sections is constructed and arranged as a compact unit in a housing

supported above the level of the coagulating bath and intermediate the forming and after-treatment sections, and in turn carries a substantially horizontal receptacle or a plurality thereof for the plasticizing liquid. A further object of the invention is to provide a ventilation system in which an inert or non-injurious gaseous medium is supplied under pressure through a space in a jacket constructed around, or formed as part of, the driving mechanism housing, passes through the external wall of the jacket about the individual driving shafts of the driven thread-handling devices, and thence is drawn upwardly and downwardly into suction ducts arranged above and below the driving mechanism housing but within a zone enclosed by suitable sash about the machine.

A further object of the invention is to provide an improved construction of spinneret "rounder" so that a narrow deep bath may be used for spinning the threads in a generally vertical direction to obtain sufficiently complete coagulation and at the same time to make it possible to start spinning from the spinneret without having to reach to the bottom of the bath. Other objects and advantages of the invention will appear from the description hereinafter in which reference to the drawing will be made.

Figure 1 is an end elevation, partially in cross-section;

Figure 1a shows in elevation an alternate form of collecting device;

Figure 2 is a plan view;

Figure 3 is a side elevation showing the coagulating bath working face;

Figure 4 is a plan view, partially in cross-section, showing the coagulating bath and associated parts in more detail.

The spinning machine has the coagulating bath working face 2, the after-treatment section 3, which are both on the same floor level, and the drying and/or collecting section 4 on a lower floor level or deck. The forming section comprises a deep, narrow trough 5 for the coagulating bath extending the length of the machine and the spinnerets 6 are arranged to spin generally vertically upwardly to the thread-advancing devices 7 disposed above the rear portion of the bath. As shown, these devices comprise two godets, the upper and larger of which is driven and the other is an idler. Alternatively, a thread advancing reel or a pair of driven godets of the same size may be used. A guide 8 serves to control the thread as it proceeds to the thread-ad-

vancing device 7 and also to remove excess coagulating liquid from the thread.

A hollow framework in the form of an intermediate longitudinal pedestal 9 supports a housing 10 for the mechanism 11 for driving the thread-handling devices including the devices 7 and the thread-advancing devices 12 in the liquid after-treatment section of the machine. The housing 10 is provided with a jacket 13 of corrosion resistant material, such as lead spaced from the walls of the housing and having openings 14 about the shaft, both drive and idler, for the thread handling devices 7 and 12. An inert or non-injurious gas, such as air, preferably dry, is forced into the space between the jacket and the main housing walls from a suitable duct 14a (Fig. 2) or ducts at one or both ends of the machine. The hollow pedestal constitutes a duct through which the foul air in the vicinity of the coagulating bath is removed, suitable openings 15 being provided in the pedestal all along the machine adjacent the top of the trough 5, and one or two suitable exhaust ducts being provided, such as at one or both ends of the machine, and being connected to exhaust fans. Similarly a duct 16 extending the length of the machine is provided in the upper region of the hood 17 comprising suitable sash means 17a by which the spinning stations of the machine are readily accessible to the operators. The duct 16 is provided with openings 18 (preferably adjustable in any conventional manner) in the base thereof facing the receptacle or receptacles 19 for the plasticizing liquid. The provision of the upper exhaust duct 16 and that in the pedestal 9 assures that the foul air will be drawn away from the operators while they are manipulating the thread in lacing up the machine or tending to it at any other time. In addition, the provision of an inert gaseous medium under elevated pressure within the jacket 13 about the housing for the driving mechanism protects this mechanism from any foul, corrosive atmosphere that may hover about the coagulating section of the machine.

The driving godets of the devices 7 are set at an acute angle to the longitudinal axis of the machine so that they are offset laterally and axially from each other in staggered relationship. The reels 12 are similarly staggered so that the threads proceed at an acute angle from the upper godets through their respective troughs 19 to their respective after-treating reels 12. By this arrangement, it is possible to obtain a long immersion through the stretch baths in troughs 19 without having the receiving ends of the reels 12 beyond the reach of operators having average arm length. Preferably, the troughs 19 are placed from three to five feet from the floor level. The troughs 19 may be supplied with liquid, such as hot water or hot dilute acid, by the downwardly extending branches 20 of the feed pipe 21 and adjacent each end with the slotted partitions 22 forming overflow chambers at each end of the trough which discharge in drains 23.

The reels 12 may be provided with a surrounding deflector or guard 24 for controlling the action of the liquids upon the threads and substantially confining the several different liquids applied to their respective treating zones along the helix. This deflector or guard may be of the same construction as that shown in either of the copending applications of Stanley and Lowe, Ser. No. 504,664, filed October 2, 1943; and Ser. No. 523,402, filed February 22, 1944. Headers 25 having branches 26 conduct the several treating

liquids to corresponding treating zones of the helix formed on the reels 12. Discharge pipes 27 connected to the extreme limits of each treating zone lead to troughs 28 which extend the length of the machine for receiving the discharge from the corresponding zones of all the reels 12. The discharge from each of these troughs may be recirculated to the appropriate header, with or without first subjecting it to recovery, replenishment, or purification processes. The troughs 28 or any selected one or more thereof may be replaced with headers connected to pipes 27 in which case the removal of liquid from the respective treating zones may be assisted by suitable suction pumps inserted in the respective headers, especially for operating in accordance with the above-mentioned application Serial No. 523,402.

An inwardly and downwardly sloping trough 29 may be disposed beneath the several troughs 28 and preferably extends to a point beyond the discharge ends of the reels 12. A trough 30 sloping toward one end, or from the middle toward both ends, of the machine serves to discharge any drainings from the trough 29.

The reels 12 are preferably removably supported at both ends, being coupled for driving at their inner ends and rotatably to a series of posts 31 which are capable of being swung outwardly on their pivots 32 for removing the reels and of being locked in reel-supporting position by the latches 33. Reels 12 are preferably driven at higher peripheral speed than the devices 7 so that a predetermined amount of stretching occurs as the threads pass through the troughs 19.

The threads proceed substantially vertically downwardly from the discharge ends of the reels 12 either to centrifugal collecting buckets 34 through the traversing funnel guides 35 as shown in Figure 1a (where alternate threads are directed by godets 36 and 37 to the opposite row of buckets) or they proceed (as illustrated in Figure 1) to any suitable form of drying means such as the heated casing 38 in which the respective thread is advanced in the form of a helix about two canted drums 39 and 40, at least one of which is driven, and then to a collecting device, such as the winding machine 41. If desired, the winding machine may be replaced by a cap-twisting or ring-twisting device.

As shown in the drawing, the bath for coagulating the filaments or threads is preferably narrow and this is necessary in order that an operator standing at the coagulating bath working face 55 of the machine can readily reach over the bath to pass the threads through the stretching troughs 19 and place them on the receiving ends of the reels 12. As shown in Figures 3 and 4, the connections to supply the spinnerets 6 with spinning material extend through apertures 42 in the outside wall 43 of the trough 5 for the coagulating bath. A bearing 44 of suitable material, preferably resistant to corrosion by the coagulating material is secured in the aperture, such as by welding, so that its axis is inclined in a horizontal plane at a small acute angle, preferably less than 25°, to the normal to the length of the machine. The "rounder" 45 preferably is made of a corrosion-resistant material, such as stainless steel tubing or piping, and has an approximately right angle bend at 46 spaced a short distance from the wall 43 of the coagulating bath trough. The portion of the rounder extending through the wall 43 is provided with a shoulder 47 and is clamped 70 within a sleeve 48 (which is rotatable within the

bearing 44) by the nut 49 engaging a threaded portion of the rounder. A hand-wheel 50 positioned outside the trough 5 is fixed upon the sleeve so that it can be used to rotate the rounder and thus swing the spinneret into and out of the trough. A washer 51 of resilient material, such as soft rubber or synthetic rubber, is provided so that it is forced by hydraulic pressure against a suitable seat or face 52 formed on the bearing 44, thereby sealing the joint against leakage. A hollow region 53 may be formed in the bearing member 44 and may be provided with a suitable drainage connection 53a (Figure 1). The sleeve 48 may be provided with grooves 54 to prevent any liquid leaking from the bath from proceeding beyond the region 53 provided with suitable drainage. An L connection 55 connects the tube 56 which receives the spinning material from the pump 57 to the rounder, a "ball and socket" joint being provided at 58 to permit rotation of the rounder 45 relative to the L 55. A spring pressed pin 59 mounted in the bracket 60 maintains the L 55 firmly in engagement with the rounded end of rounder 45.

The rounder 45 has a long straight portion extending from the bend 46 which merges at 45a with a portion which curves back so that the spinneret 6 at the end of the rounder directs the filaments or thread produced thereby in an upward direction. This curved portion is bent at 45a so that it lies in a plane approximately parallel to the wall 43 of the trough when disposed in spinning position. It will be seen from Figure 2 that when the rounder is swung into inoperative position, the spinneret is directed downwardly over the waste or draining trough 61 which may be provided with removable waste trays 62. Preferably, the width of the inner web 63 of the bracket 60 is so correlated with the disposition of the spokes 64 of the handwheel 50 that the upper and lower edges of the web 63 serve as detents to limit the rotation of the handwheel to dispose the spinneret in operating position and in inoperative position over the waste trough 61. It will be seen from Figure 4 that the rounders are so constructed and arranged as to permit immersion of the spinneret to a great depth, swinging the spinneret to a point near the bath surface for lacing up the machine and swinging the spinneret to a point over the waste trough, without interfering with each other and the walls of the trough in spite of its narrowness and depth. In Figure 2, the dotted line a—b shows the extreme limit of movement of the rounder away from the wall 43 of trough 5.

In starting the spinning operation, the operator turns the handwheel 50 until the spinneret is at or near the surface of the coagulating bath, threads up the thread handling device 7 and as the thread is taken up thereby he lowers the spinneret to the bottom of the trough 5, and then takes the thread from the device 7 through one of the stretch baths to the corresponding reel 12. An operator on the other working face of the machine takes the thread as it is discharged from the reel 12 and drops it to the floor below where another operator receives it and laces up whatever collecting and/or drying devices are there. There is no necessity for the operators to carefully synchronize their activities in that each section of the machine can continue to function while waiting for the operator in the next section in advance to send the thread on its way to the next section.

A screen 66 and a plate 67 separate the bath

trough 5 from the draining trough 61. The plate is adjustably mounted so that the depth of the coagulating bath may be controlled readily.

It is to be understood that changes and variations may be made without departing from the spirit and scope of the invention as defined by the following claims.

I claim:

1. A machine for continuously producing artificial thread, said machine being substantially entirely enclosed and having a framework comprising a hollow pedestal extending the length of the machine, a housing supported on the pedestal, a jacket about the housing having portions thereof spaced from the walls of the housing to provide at least one channel extending the length of the machine, shafts extending through the walls of the housing and jacket at regions where they are spaced apart, thread-handling devices carried by the shafts outside the jacket, driving mechanism for at least some of the shafts inside the housing, means for introducing a non-injurious gaseous medium into the channel, and means for withdrawing foul atmosphere from the regions about the housing through the hollow pedestal.
2. A machine for continuously producing artificial thread, said machine being substantially entirely enclosed and having a framework comprising a hollow pedestal extending the length of the machine, a housing supported on the pedestal, a jacket about the housing having portions thereof spaced from the walls of the housing to provide at least one channel extending the length of the machine, shafts extending through the walls of the housing and jacket at regions where they are spaced apart, thread-handling devices carried by the shafts outside the jacket, driving mechanism for at least some of the shafts inside the housing, means for introducing a non-injurious gaseous medium into the channel, a trough for a coagulating medium along one side of the pedestal, apertures in the pedestal above and adjacent to the trough, and means for reducing the pressure within the pedestal.
3. A machine for continuously producing artificial thread, said machine being substantially entirely enclosed and having a framework comprising a hollow pedestal extending the length of the machine, a housing supported on the pedestal, a jacket about the housing having portions thereof spaced from the walls of the housing to provide at least one channel extending the length of the machine, shafts extending through the walls of the housing and jacket at regions where they are spaced apart, thread-handling devices carried by the shafts outside the jacket, driving mechanism for at least some of the shafts inside the housing, means for introducing a non-injurious gaseous medium into the channel, a trough for a coagulating medium along one side of the pedestal, apertures in the pedestal above and adjacent to the trough, means for reducing the pressure within the pedestal, an open trough means carried on the jacketed housing, and an exhaust duct spaced thereabove.
4. A machine for continuously producing artificial thread comprising a forming section and a liquid after-treatment section arranged side by side and each comprising a plurality of associated single end spinning stations, the forming section comprising a coagulating trough, additional approximately horizontal trough means above the coagulating trough, and thread handling devices for conveying the threads from the coagulating

trough to the additional trough means, the liquid after-treatment section comprising a plurality of thread-advancing devices, one only for each spinning station, means for applying a plurality of different treating liquids separately to several axially spaced zones of each of the thread-advancing devices, driving means for at least some of the thread handling devices and driving means for the thread-advancing devices, both of said driving means being disposed in a common housing arranged intermediate of portions of the two sections.

5. A machine for continuously producing artificial thread comprising a forming section and a liquid after-treatment section arranged side by side and each comprising a plurality of associated single end spinning stations, the forming section comprising a coagulating trough, additional approximately horizontal trough means above the coagulating trough, and thread handling devices for conveying the threads from the coagulating trough to the additional trough means, the liquid after-treatment section comprising a plurality of thread-advancing devices, one only for each spinning station, means for applying a plurality of different treating liquids separately to several axially spaced zones of each of the thread-advancing devices, driving means for at least some of the thread handling devices and driving means for the thread-advancing devices, both of said driving means being disposed in a common housing arranged intermediate of portions of the two sections, the additional trough means being supported by the housing.

6. A machine for continuously producing artificial thread comprising a forming section and an after-treatment section arranged side by side on approximately the same floor level, a trough for a coagulating bath in the first section running the length of the machine adjacent one working face thereof, a spinneret in the bath, trough means arranged approximately horizontally in the forming section above and behind the coagulating trough and alongside the after-treating section, a thread-advancing device in the forming section along one side of the horizontal trough means arranged to withdraw the threads from the spinneret in a generally vertical direction, a thread-advancing device in the after-treating section having its thread-receiving end along the other side of the horizontal trough means and its discharging end extending away therefrom to the other working face of the machine, and means for supplying a plurality of different treating liquids separately to several axially spaced zones on the thread-advancing device in the after-treating section.

7. A machine for continuously producing artificial thread comprising a forming section and an after-treatment section arranged side by side on approximately the same floor level, a trough for a coagulating bath in the first section running the length of the machine adjacent one working face thereof, a spinneret in the bath, trough means arranged approximately horizontally in the forming section above and behind the coagulating trough and alongside the after-treating section, a thread-advancing device in the forming section along one side of the horizontal trough means arranged to withdraw the threads from the spinneret in a generally vertical direction, a thread-advancing device in the after-treating section having its thread-receiving end along the other side of the horizontal trough means and its discharging end extending away therefrom to

the other working face of the machine, means for supplying a plurality of different treating liquids separately to several axially spaced zones on the thread-advancing device in the after-treating section, all of the liquid after-treatments being applied to said thread-advancing device, another thread-advancing device for receiving the thread discharged from the liquid after-treating thread-advancing device, and means for drying the thread as it passes over the last-mentioned thread-advancing device.

8. A machine for continuously producing artificial thread comprising a forming section and an after-treatment section arranged side by side on approximately the same floor level, a trough for a coagulating bath in the first section running the length of the machine adjacent one working face thereof, a spinneret in the bath, trough means arranged approximately horizontally in the forming section above and behind the coagulating trough and alongside the after-treating section, a thread-advancing device in the forming section along one side of the horizontal trough means arranged to withdraw the threads from the spinneret in a generally vertical direction, a thread-advancing device in the after-treating section having its thread-receiving end along the other side of the horizontal trough means and its discharging end extending away therefrom to the other working face of the machine, said thread-advancing devices being arranged with their upper thread-carrying levels just below the liquid level in the trough means so that the thread passes from one to the other directly through the trough means below the liquid level therein, and means for supplying a plurality of different treating liquids separately to several axially spaced zones on the thread-advancing device in the after-treating section.

40 9. A machine for continuously producing artificial thread comprising a forming section and an after-treatment section arranged side by side on approximately the same floor level, a trough for a coagulating bath in the first section running the length of the machine adjacent one working face thereof, a spinneret in the bath, trough means arranged approximately horizontally in the forming section above and behind the coagulating trough and alongside the after-treating section, a thread-advancing device in the forming section along one side of the horizontal trough means arranged to withdraw the threads from the spinneret in a generally vertical direction, a thread-advancing device in the after-treating section having its thread-receiving end along the other side of the horizontal trough means and its discharging end extending away therefrom to the other working face of the machine, means for supplying a plurality of different treating liquids separately to several axially spaced zones on the thread-advancing device in the after-treating section, the thread-advancing devices in both sections being arranged with their axes approximately parallel and set at a perpendicular to a direction making a small acute angle with the longitudinal direction of the machine.

70 10. A machine for continuously producing artificial thread comprising a forming section and an after-treatment section arranged side by side on approximately the same floor level, a trough for a coagulating bath in the first section running the length of the machine adjacent one working face thereof, a spinneret in the bath, trough means arranged approximately horizontally in the forming section above and behind the

coagulating trough and alongside the after-treating section, a thread-advancing device in the forming section along one side of the horizontal trough means arranged to withdraw the threads from the spinneret in a generally vertical direction, a thread-advancing device in the after-treating section having its thread-receiving end along the other side of the horizontal trough means and its discharging end extending away therefrom to the other working face of the machine, said thread-advancing devices being arranged with their upper thread-carrying levels just below the liquid level in the trough means so that the thread passes from one to the other directly through the trough means below the liquid level therein, means for supplying treating liquids to a plurality of zones on the thread-advancing device in the after-treating section, the thread-advancing devices in both sections being arranged with their axes approximately parallel and set at a perpendicular to a direction making a small acute angle with the longitudinal direction of the machine.

11. A machine having two working faces for continuously producing artificial thread comprising a housing extending throughout the length of the machine intermediate of the working faces thereof, a plurality of spinnerets spaced at intervals along one working face of the machine, means for applying a coagulating liquid to the spinnerets, a plurality of thread-handling devices mounted on one side of the housing and projecting therefrom toward the first-mentioned working face of the machine for withdrawing the threads upwardly from the spinnerets to a level above the housing, means in the housing for driving at least some of the devices, a plurality of thread-advancing devices mounted on the housing and projecting from the other side of the housing toward the other working face of the machine, means in the housing for driving the thread-advancing devices to advance thread from their ends near the housing to their ends away from the housing, and means for supplying treating liquids to the thread-advancing devices.

12. The machine of claim 11 comprising trough means supported on top of the housing for applying a liquid to the threads as they pass from the thread-handling devices to the thread-advancing devices.

13. The machine of claim 11 in which the upper level of the thread-handling devices is at substantially the same height as the upper level of the thread-advancing devices.

14. The machine of claim 11 in which the thread-advancing devices are reels.

15. The machine of claim 11 in which the thread-handling devices and the thread-advancing devices are arranged with their axes approximately parallel and set at a perpendicular to a direction making a small acute angle with the longitudinal direction of the machine.

16. The machine of claim 11 comprising a supporting structure for the housing having a wall facing the spinnerets, apertures in the wall above and adjacent the upper level of the coagulating liquid, means for enclosing the two faces of the machine, and means for producing a differential in the pressures on the opposite sides of the apertures to sweep foul air away from the zone above the coagulating liquid.

17. A machine having two working faces for continuously producing artificial thread comprising a housing extending throughout the length

of the machine, a trough for a coagulating bath extending the length of the machine along one side of the housing, a plurality of spinnerets spaced at intervals along the trough adjacent one working face of the machine, a plurality of thread-handling devices mounted on the housing and projecting from one side thereof toward the first-mentioned working face of the machine for withdrawing the threads upwardly from the spinnerets, means in the housing for driving the thread-handling devices, a plurality of thread-advancing devices mounted on the housing and projecting from the other side thereof to the other working face of the machine, means in the housing for driving the devices to advance thread from their thread-receiving ends adjacent the housing to their thread-discharge ends away from the housing, and means for supplying treating liquids to the thread-advancing devices.

18. A machine having two working faces for continuously producing artificial thread comprising a housing extending throughout the length of the machine, a trough for a coagulating bath extending the length of the machine along one side of the housing adjacent a lower level thereof, a plurality of spinnerets spaced at intervals along the trough adjacent one working face of the machine, a plurality of thread-handling devices mounted on the housing adjacent an upper level thereof and projecting from one side thereof toward the first-mentioned working face of the machine for withdrawing the threads upwardly from the spinnerets, means in the housing for driving the thread-handling devices, a plurality of thread-advancing devices mounted on the housing adjacent an upper level thereof and projecting from the other side thereof to the other working face of the machine, means in the housing for driving the devices to advance thread from their thread-receiving ends adjacent the housing to their thread-discharge ends away from the housing, and means for supplying treating liquids to the thread-advancing devices.

19. A machine having two working faces for continuously producing artificial thread comprising a housing extending throughout the length of the machine intermediate of the working faces thereof, a plurality of spinnerets spaced at intervals along one working face of the machine, means for applying a coagulating liquid to the spinnerets, a plurality of thread-handling devices mounted on one side of the housing and projecting therefrom toward the first-mentioned working face of the machine for withdrawing the threads upwardly from the spinnerets to a level above the housing, means in the housing for driving at least some of the devices, a plurality of thread-advancing devices mounted on the housing and projecting from the other side of the housing toward the other working face of the machine, the thread-handling devices and the thread-advancing devices being arranged with their axes approximately parallel and set at a perpendicular to a direction making a small acute angle with the longitudinal direction of the machine, means in the housing for driving the thread-advancing devices to advance thread from their ends near the housing to their ends away from the housing, means for supplying treating liquids to the thread-advancing devices, and trough means supported on top of the housing for applying a liquid to the threads as they pass from the thread-handling devices to the thread-advancing devices.

11

20. The machine of claim 19 in which the upper level of the thread-handling devices is at substantially the same height as the upper level of the thread-advancing devices.

21. The machine of claim 19 in which the thread-advancing devices are reels.
